SECTION LINING DEVICE

Edward Sokolik, New Brighton, Minn.

Application August 24, 1945, Serial No. 612,448

3 Claims. (Cl. 33—108)

1

My present invention relates to a combination section lining device for drawing parallel lines to indicate sections in mechanical drawings.

The object of this invention is to facilitate by speed, precision, uniformity and ease, the drawing by a writing instrument of parallel lines on a drawing to indicate a section.

To the above end, the invention consists of the novel construction and arrangement of parts hereinafter described and defined in the claims.

In the accompanying drawing, which illustrates the invention, like characters indicate like parts throughout the several views.

Referring to the drawings:

Fig. 1 is a plan view of my reversible section lining device;

Fig. 2 is an end elevation of the same;

Fig. 3 is a fragmentary detail view in section taken on the line 3—3 of Fig. 1, on an enlarged scale; and

Fig. 4 is a view corresponding to Fig. 3 but showing a non-reversible section lining device.

The reversible section lining device shown in Figs. 1, 2 and 3 includes a relatively thin, rectangular frame 5 for a multiplicity of narrow, parallel ribs 6 that are integral therewith. These ribs 6 are laterally spaced to leave narrow writing instrument passageways 7 therebetween. As shown, the ribs 6 extend at angles of forty-five degrees, but, of course, may extend at any desired angle. The ribs 6 are spaced inwardly from each face of the frame 5 to leave a clearance space 8 for a piece of paper or Bristol board lying on a table, not shown. In each end member of the frame 5 is a paper passageway or slot 9 that branches and leads to clearance spaces 8. The clearance spaces 8 and the passageway 9 extend the full distance between the side members of the frame 5.

From a medial plane between the faces of the frame 5, the sides of each rib 6 converge to narrow upper and lower edges. This formation of the ribs 6 materially reduces the width of the passageways 7 at the wide portions of said ribs which guide a writing instrument. The upwardly diverging sides of adjacent ribs 6 make it extremely easy to insert a writing instrument into the passageways 7. Also the downwardly diverging sides of the ribs 6 prevent ink from being drawn from a pen by capillary attraction.

To place a piece of paper or Bristol board in the section lining device, the same is inserted endwise into the passageway 9 at one end of the frame 5 and directed into the lowermost branch of said passageway. From the respective pas-

2

sageway 9, the paper is fed in the lower clearance space 8 under the ribs 6 and into the passageway 9 in the other end member of the frame 5. The paper under the ribs 6 will lie on the table on which the section lining device rests and be held against transverse shifting movement by the side members of the frame 5. In placing the paper in the section lining device, one end portion thereof is left projecting outwardly of the frame 5 so that said paper may be manipulated in the section lining device. The ribs 6 are connected by several rows of reinforcing ribs 10. These reinforcing ribs 10 are integral with the ribs 6 and permit a writing instrument to be placed thereover and thereunder to continue a line being drawn that was interrupted by one of said ribs.

Obviously, by reversing the section lining device, the inclination of the ribs 6 will be reversed.

The section lining device shown in Fig. 4 is non-reversible and parts thereof that correspond to like parts in Figs. 1, 2 and 3 are given the same reference numerals followed by a prime.

The section lining devices are made of a transparent material.

From what has been said, it will be understood that the invention described is capable of modifications as to details of construction and arrangement within the scope of the invention herein disclosed and claimed.

What I claim is:

1. A section lining device comprising a rectangular open frame having a plane face, the opposite ends of the frame having inwardly extending slots, the outer ends of the inwardly extending slots being parallel to the plane of the face and the inner ends of the slots diverging towards the plane of the face and terminating inwardly of the plane of the face for feeding a sheet of writing material thereto; spaced ribs lying within said frame, the edges of said ribs adjacent said face being coplanar and spaced from said face by an amount substantially equal to the thickness of a sheet of writing material, whereby such sheet may be extended through said slots with a portion of said sheet lying between the plane of said face and said rib edges.

2. A device as claimed in claim 1 wherein the frame has plane opposite faces and the inner ends of the slots diverge towards both opposite faces.

3. A device as claimed in claim 2 wherein the spaced ribs are beveled towards both faces.

EDWARD SOKOLIK.
